DOMESTIC REFRIGERATOR

Carl G. Vretman, Atlanta, Ga.

Application March 6, 1939, Serial No. 260,143

7 Claims. (Cl. 62—95)

This invention relates to refrigerators, particularly of the type used for household purposes, and has for a primary object to provide an extremely simple arrangement of the cooling elements in the housing which will divide the inside of the chamber or box into a plurality of compartments which, by reason of the relative location of the cooling elements, will tend to maintain said compartments at different relative temperatures.

Another object of the invention is to provide a freezing unit which will not require a drip pan to catch such small quantity of moisture of condensation as may occur, and in which said moisture, if any, will not fall upon the contents of the refrigerator but will run down the side walls.

A further object of this invention is to provide a cooling unit of such construction that the absorption of heat from the compartments on one side thereof will be substantially uniform throughout all unit areas thereof, so as to avoid irregular freezing and accumulation of frost.

Still another object of this invention is to provide a refrigerator box or housing divided into several compartments which, when the door is closed, are completely and tightly sealed from each other so as to prevent interchange of atmosphere and temperature exchange, but which, when the door is open, will be open for free access thereto.

A further object of this invention is to provide a refrigerator having a plurality of compartments, one of which is a freezing compartment, in which the food compartments are cooled by the same cooling elements as the freezing compartment, but in which the atmosphere and humidity of the food compartments will not have access to the freezing compartment, whereby frosting of the freezing compartment and drying of the atmosphere of the food compartments are reduced.

A still further object of the invention is to provide a freezing unit of a type which can be cleared of frost or ice or other adhering matter quickly and conveniently by scraping substantially plane, smooth surfaces and without the necessity of putting the refrigerating apparatus out of operation.

An embodiment serving to illustrate the invention is shown in the accompanying drawing, in which

Fig. 1 is a side sectional view of the refrigerator; and

Fig. 2 is an elevational sectional view.

In the drawing, numerals 1 indicated generally an insulated box having a door 2 at the

front and supported above a compartment 3 for the refrigeration mechanism indicated generally by numeral 4. The refrigeration mechanism may be of any suitable type, such as a conventional mechanical compression and expansion type, or a gas absorption type. As the present invention does not directly concern the mechanism for compressing the refrigerant, this mechanism need not be particularly described herein, but is diagrammatically represented in the drawing as a conventional mechanical unit comprising a compressor, a condenser, a receiver, and connections for conducting the refrigerant to an expansion valve 5 located in close proximity to the cooling elements 7 and 8. The cooling elements 7 and 8 may comprise evaporators 9 and 10 in the form of flat coils or else vacuum plates of more or less conventional character per se and liquid heat transfer plates 13 and 14 located on the top and bottom of the upper and lower evaporators 9, 10 respectively. The evaporators are preferably connected in series, and one of said evaporators, for instance, the lower evaporator 9, receives the expanding refrigerant from the expansion valve 5, and from said lower evaporator 9 the refrigerant passes through 11 to the upper evaporator 10, from which it then passes through return pipe 12 back to the compressor or the like.

The compartment 23 between the cooling elements 7 and 8 constitutes the coldest compartment of the refrigerator, which is used for making ice or frozen deserts, for keeping meat, or for other purposes where low temperatures are required. Freezing trays 17 are shown in the freezing compartment 23 in broken lines.

The liquid heat transfer plates are entirely closed and fit closely against the side and back walls of the refrigerator box and may be soldered or otherwise integrally connected with the walls so as to prevent air or liquid from passing between their edges and the walls, and may be soldered to the evaporators to prevent moisture from getting therebetween. The liquid plates are filled with a liquid which will not freeze at the temperature to which it is to be subjected. At the front edges of the vacuum plates and liquid plates, resilient packings such as rubber strips 18 and 19 are secured for sealing against the inside of the door when the door is closed, thus preventing passage of air or liquid.

The purpose of the liquid plates is to make the temperature on their sides opposite the cooling elements uniform, and possibly may retard heat transfer to such extent that said opposite sides may remain above freezing at all times.

It is apparent that along the surfaces of the vacuum plates the portions closely adjacent an interior pipe will be colder than the portions adjacent the spaces or gaps between the interior pipes. This is undesirable, as it would cause freezing of ice or frost in ridges along the colder portions. However, this unevenness of temperature cannot penetrate through the liquid plates but, due to the action or local movement within the liquid, is made uniform at the opposite surfaces.

The division walls forming the coldest compartment are thus constituted by the cooling elements which include the vacuum plates and liquid plates which are smooth and substantially plane on their surfaces. However, the lower surface of the lower liquid plate is preferably made to slope slightly downwardly from a central line toward the sides (Fig. 2) so that moisture of condensation or melted frost, if any, will run to the sides instead of dropping upon the contents of the lower compartment.

The walls of the freezing compartment are located in the refrigerator at any desired location depending principally upon the relative temperatures desired to be maintained in the upper and lower compartments. If it is desired that the upper compartment be colder than the lower compartment, the division walls constituted by the cooling elements and liquid plates should be located considerably closer to the top than to the bottom. The upper compartment thus being the smaller requires less cooling to attain the lower temperature but, due to the fact that heat tends to rise, the efficiency of heat transfer from the lower compartment to the lower liquid plate is higher than from the upper compartment to the upper liquid plate. This tends to make the lower compartment the colder so that it is necessary that the upper compartment be made even smaller than would otherwise be the case, in order that it shall have the lower temperature of the two. It will be observed that in the illustrated embodiment the upper compartment is shown as being only about half the size of the lower compartment. This relation of sizes can be varied at will and if it is desired that the lower compartment be the colder, it is only necessary to arrange the cooling elements at a lower position.

In operation the freezing compartment, being located directly between the two vacuum plates 9 and 10, is maintained at a low temperature for freezing its contents. The upper compartment 21 being comparatively small is the next coldest compartment. The floor of this compartment 22 is cooled by liquid plate 14 in contact with vacuum plate 10, serves to cool the compartment, and the liquid plate serves to make the temperature uniform over the entire area of the floor. As the upper surface of the liquid plate is smooth, accumulations of frost, if any, may be scraped off the plate so that it will hardly ever be necessary to turn off the refrigeration apparatus for defrosting. In a similar way the lower compartment 22 is cooled by liquid plate 13, but the compartment 22 being larger than the upper compartment is maintained at a higher temperature. However, the relative temperature can be changed by changing the position of the cooling elements so that the relative sizes of the compartments is changed. If moisture should ever be present on the lower face of liquid heat transfer plate 13, it will run to the sides and down the side walls instead of dropping upon

the contents of the compartment, this action being due to the lateral downward slope of the lower face of said plate.

In the embodiment illustrated two evaporators connected in series have been disclosed, but, if desired, one of these may be omitted, in which case a liquid heat transfer plate or a plain sheet metal plate will serve as the partition for the freezing compartment.

Furthermore, as a further alteration, one or both of the evaporators may extend only partially across the chamber, but in this case the liquid or metal heat transfer plates should extend the entire width and serve as the partitions.

I claim as my invention:

1. In a domestic refrigerator, walls forming a chamber, a cooling element in said chamber dividing off a part of said chamber as a freezing compartment while the remainder serves as a cold storage compartment, said cooling element comprising an evaporator in the form of a flat plate toward the freezing chamber and a flat container entirely closed from and free of the refrigerant and being filled with liquid which will not freeze at the temperature to which it is to be subjected, said container being located on the side of the evaporator plate toward the cold storage compartment for distributing the cooling effect of the evaporator and retarding heat transfer from the cold storage compartment to the evaporator.

2. In a domestic refrigerator, walls forming a chamber, a cooling element in said chamber dividing off a part of said chamber as a freezing compartment while the remainder serves as a cold storage compartment, said cooling element comprising an evaporator in the form of a flat plate toward the freezing chamber and a flat container entirely closed from and free of the refrigerant and being filled with liquid which will not freeze at the temperature to which it is to be subjected, said container being located on the side of the evaporator plate toward the cold storage compartment for distributing the cooling effect of the evaporator and retarding heat transfer from the cold storage compartment to the evaporator.

3. In a domestic refrigerator, walls forming a chamber, a cooling element in said chamber dividing off a part of said chamber as a freezing compartment while the remainder serves as a cold storage compartment, said cooling element comprising an evaporator in the form of a flat plate toward the freezing chamber and a flat container entirely closed from and free of the refrigerant and being filled with liquid which will not freeze at the temperature to which it is to be subjected, said container being located on the side of the evaporator plate toward the cold storage compartment for distributing the cooling effect of the evaporator and retarding heat transfer from the cold storage compartment to the evaporator, the adjacent surfaces of said evaporator and liquid container being integrally united to improve heat transfer and prevent water or ice from entering therebetween.

4. In a domestic refrigerator, walls forming a chamber, a cooling element in said chamber dividing off a part of said chamber as a freezing compartment while the remainder serves as a cold storage compartment, said cooling element comprising an evaporator in the form of a flat plate toward the freezing chamber and a flat container entirely closed from and free of the refrigerant and being filled with liquid which will not freeze at the temperature to which it is to be subjected, said container being located on the side of the evaporator plate toward the cold storage compartment for distributing the cooling effect of the evaporator and retarding heat transfer from the cold storage compartment to the evaporator, the adjacent surfaces of said evaporator and liquid container being soldered together to improve heat transfer and prevent water or ice from entering therebetween.

5. In a refrigerator, walls and a door forming a chamber, a pair of flat cooling elements extending horizontally entirely across the chamber and spaced apart from each other so as to form a freezing compartment therebetween and upper and lower storage compartments above and be-

low respectively, said cooling elements including flat evaporators and flat liquid-containing chambers adjacent said evaporator on the sides thereof of adjacent the upper and lower compartments respectively for eliminating temperature differences in the cooling surfaces of the cooling elements.

5. In a refrigerator, walls and a door forming a chamber, a pair of flat cooling elements extending horizontally entirely across the chamber and spaced apart from each other so as to form a freezing compartment therebetween and upper and lower storage compartments above and below respectively, said cooling elements comprising evaporators and liquid-containing chambers adjacent said evaporators on the sides thereof adjacent the upper and lower compartments respectively for eliminating temperature differences in the cooling surfaces of the cooling elements, the bottom surface of the lower liquid chamber sloping downwardly laterally from a central line to cause condensate to flow to the sides and down the walls instead of dropping upon the contents of the lower compartment.

6. In a refrigerator, walls and a door forming a chamber, a pair of flat cooling elements extending substantially horizontally entirely across the chamber and spaced apart from each other so as to form a freezing compartment therebetween and upper and lower storage compartments above and below respectively, said cooling elements comprising liquid-containing chambers on the sides thereof adjacent the upper and lower compartments respectively for eliminating temperature differences in the surfaces of the cooling elements toward said storage compartments, said cooling elements having smooth and substantially plane free surfaces from which frost may be scraped.

ments above and below respectively, said cooling elements comprising flat evaporators and liquid-containing chambers adjacent said evaporators on the sides thereof adjacent the upper and lower compartments respectively for eliminating temperature differences in the cooling surfaces of the cooling elements, said liquid chambers being tightly sealed at their edges against the side walls and back, and elastic sealing strips at the door edges of said chambers for sealing against the door when closed, whereby water vapor from food in the upper and lower compartments is prevented from reaching the freezing compartment.

7. In a refrigerator, walls and a door forming a chamber, a pair of flat cooling elements extending horizontally entirely across the chamber and spaced apart from each other so as to form a freezing compartment therebetween and upper and lower storage compartments above and below respectively, said cooling elements comprising liquid-containing chambers on the sides thereof adjacent the upper and lower compartments respectively for eliminating temperature differences in the surfaces of the cooling elements toward said storage compartments, said cooling elements having smooth and substantially plane free surfaces from which frost may be scraped.
